GENERAL MOTORS RESEARCH CORPORATION, OF DETROIT, MICHIGAN, A CORPORA-
TION OF DELAWARE

ENGINE MOUNTING

Application filed December 28, 1925. Serial No. 77,885.

The invention relates to means for supporting bodies which are subject to vibratory or oscillatory movements and for preventing transmission of such movements to the base 5 whereby the body is sustained or suspended. It finds especial utility in connection with motors or machines in which a tendency to vibratory movements is produced by unbalanced inertia forces due to the actuation of 10 unbalanced moving parts.

Although obviously of more generic application, the invention will be herein described as applied to an internal combustion engine of the four cylinder type. In this 15 embodiment of the invention it will have as its function the prevention of transmission to the frame or bed of the engine, for example, to the frame of an automobile in which the engine constitutes the source of power, 20 of the vibrations of the engine body due chiefly to unbalanced inertia forces resulting from the piston and connecting rod motions.

It is well known that an engine of the type mentioned is not inherently balanced as to 25 its piston movements, and as a result, when unrestrained, the entire engine moves slightly in a direction parallel to the cylinder center lines at twice crankshaft frequency. It is also well-known that the cylinder block 30 tends to sway slightly from side to side at double crankshaft frequency, this being known as piston inertia torque, and may be explained as follows:

When the crank throws are in a vertical 35 position, all pistons are at a standstill so they have no kinetic energy. Ninety degrees later, all four pistons are moving at a high velocity. This energy is drawn from and returned to the flywheel twice each revolution 40 of the crankshaft. Since the energy of the system is constant, the flywheel is alternately accelerated and decelerated, such force having a reaction on the cylinder block in the form of piston side pressures which tend to 45 sway the block back and forth through a definite angle.

Therefore, the resultant of the vertical motion due to piston unbalance which manifests 50 itself principally at the front of the engine, since the actuating force is forward of the

center of mass of the motor unit, combines with the rocking action due to piston inertia torque, this latter motion manifesting itself in the rear motor legs as an up and down movement. The two legs, moving in opposite 55 direction, give a different motion at the three points of suspension, but all of the same frequency, which is twice the rate of rotation of the crankshaft.

Furthermore we have found that the actual 60 amplitude of these up and down vibratory movements is relatively small and is independent of engine speed. Of course more energy is exerted at higher engine speeds so that the frame and attached parts are forced 65 to vibrate with the engine, and these vibrations become especially annoying and undesirable when their rate comes into resonance with any particular part of the car, such as fenders, cowl, etc.

In accordance with the present invention 70 it is proposed to support the vibrating body, as the engine, by means which neutralizes or compensates for the vibrations, in other words, permitting the vibrations to take place 75 without transmission of their energy to the final sustaining or suspending frame or foundation herein referred to generally as the "base". To this end we have provided 80 means whereby, when the engine tends to move upward at a point of support under the influence of the vibrations, the supporting means moves upwardly with it to an extent substantially equal to the natural amplitude of the vibrational movement, and similarly, when the engine tends to move downwardly, the supporting means goes with it, thus varying the dimensions of the supporting 85 means between the base and the vibrating body by an amount equivalent to the amplitude of the vibrations without varying the force exerted upon the base through the points of support.

The direction and extent of variation in 90 the position of the supporting means at each of the points of support and the phase relation of the movements at the different points may be determined empirically or otherwise by observation or computation of the characteristics of the vibrations produced at each 95

point. Suitable means may then be provided at each point of support to effect the necessary neutralizing or compensating movements.

6 In the accompanying drawings, in which is shown by way of illustration one form of adaptation of the invention to the mounting of an internal combustion engine upon the chassis of an automobile,

10 Fig. 1 is a side elevation, with parts broken away, showing a four-cylinder engine mounted upon chassis frame members;

Fig. 2 is an end elevation, partly in section, on line 2—2 of Fig. 1;

15 Fig. 3 is a front end elevation partly in section, of the structure shown in Fig. 1;

Fig. 4 is a plan view, partly in section, of the engine mounting, on the left side of Fig. 2;

20 Fig. 5 is an enlarged detail view of the lever-actuating means also shown in Fig. 2; and

Fig. 6 is a plan view of the details shown in Fig. 5.

25 Referring to the drawings, 10 indicates an internal combustion engine having cylinders 11, 12, 13, 14, crank case including upper and lower parts 15, 16, and fly wheel housing 17. These parts together with the pistons operating through connecting rods upon the crankshaft 18 may be of any usual or suitable construction. The usual cam shaft 19 is illustrated to be actuated in the customary manner at half crankshaft speed.

30 The engine base in this instance comprises a pair of longitudinal side frame or chassis members, 20, 21, and transverse frame members 22, 23, shown as positioned respectively at the front and rear of the engine crank case, member 23 being located between the crank casing and the fly wheel housing. The engine is shown as being provided with three points of support corresponding to the well known "three point suspension". One of 45 these points, indicated as A, is adjacent to the front end of the engine, and the other two, indicated as B and C respectively, are adjacent to the rear of the engine and upon opposite sides thereof.

50 The supporting means at the point A is illustrated in Fig. 3, the front cover of the crank case being removed to show parts which may be located within the casing. At this point the engine is supported upon a member 55 illustrated as a post secured at its base to the cross member 22 and extending at its upper end into the interior of the crank case. The upper end of the post is provided with a bearing for reception of the pivot or fulcrum 26 of a lever 27. The shorter end of the lever is formed at 28 to seat in a bearing 29 which may be a part of the crank case. The longer end of the lever rests against a cam 30 formed upon the cam shaft 19. As the 60 cam shaft rotates, therefore, the lever is caused

to oscillate about the fixed point of support at 26, thereby permitting the crank case, the engine, and parts supported thereby constituting the vibrating mass, supported upon the short end of the lever at 29, to rise and descend alternately. The timing of the operation and the proportions of the parts are so determined that the upward and downward movements thus permitted are equivalent to and synchronous with the vibrations to be 75 neutralized. The engine as a whole is therefore permitted to vibrate without varying the force exerted by it, due to its mass, upon the supporting post, and as a result, the effect of the vibrations is not transmitted to the frame 80 or base.

A somewhat similar structure may be utilized at the points B and C. At the point B the cross member 23 carries a bracket 31 having arms 32, 33, apertured to receive a pivot pin 34. The fly wheel housing 17 carries a bracket 35, having arms 36, 37, apertured to receive the pin 38. The lever 39 is journaled upon pin 38 and fulcrumed at its shorter end upon pin 34. The longer arm 90 of the lever extends to a point in proximity to the rear end of the cam shaft 19 which is here formed with a cam 40. A plunger 41 mounted in a bearing block 42 positioned in a bore in the crank case 15, is arranged to engage cam 40 and the end of lever 39 and cause reciprocation of the lever by the action of the cam. In this case the vibrating body supported by bracket 35 upon pin 38 is permitted to oscillate about the point of support 95 at 34. These oscillations, being made synchronous with the normal vibrations of the body, will permit the vibrations to take place without being transmitted to the base.

At the point C a bracket 45 carried by the 105 fly wheel housing supports a pin 46. A bracket 47 carried by the member 23 supports a pivot pin 48. A lever 49 is journaled upon pin 46 and fulcrumed at its shorter end upon pin 48. The longer arm of the lever extends to a point near the end of lever 39 and is arranged to rest upon a plunger 50 reciprocably mounted in the block 42 and actuated by cam 40. The arrangement of parts and the operation at point C are similar to those 115 at point B and will be readily understood from the description already given. In the structure as shown, since the cam shaft is at one side of the engine, the lever 49 is shorter than the lever 39. The pivots 46 and 48 120 therefore are nearer each other than pivots 34 and 38. This may require that one, at least, of the pivot pins be relatively small, as shown at 48. It will be noted that the plungers 41 and 50 are angularly displaced relative to 125 the axis of cam 40. This angular displacement corresponds to the difference in phase between the vibrations at the point B and those at the point C. By suitably positioning the levers and plungers this angular dis- 130

placement may be made as great or as small as may be necessary without requiring the use of separate cams for the two levers, although the latter may be employed if desired.

- 5 The vibrations due to piston action in the four cylinder engine are of a frequency twice that of the crank shaft rotations, therefore, if a cam or other actuating device placed upon the crankshaft were used to effect the variations 10 in position of the points of support such cam would have to produce two oscillations or actuations for each rotation. Since the cam shaft rotates at half crankshaft speed it is necessary that the cam or actuator located upon the cam shaft be arranged to produce 15 four actuations per rotation. The cams shown therefore each have four cam projections.

The cam shaft has been selected for illustration herein as the means for actuating the oscillatory supporting devices. It will be clear, however, that any other suitable moving part may be thus utilized. In the case of machines other than engines any shaft 20 adapted to produce the desired frequency of impulses may be employed, or a separate actuating means may be provided.

The exact phase relationship of the movement of the vibrating body, as the engine 25 block, to the cycle of movements of the unbalanced parts, as the reciprocating elements of the engine, may be most conveniently determined empirically. For this purpose the machine or engine may be supported upon 30 very long and flexible springs and set into operation. The direction, amplitude and phase relationship of the vibratory movements may then be readily observed. In the case of an engine of the type illustrated, 35 viz., a four cylinder vertical engine with the two intermediate cranks on the same side of the crankshaft and at 180° from the two end cranks, the direction of the vibrations at the points of support will be approximately vertical. The center of gravity of the reciprocating parts in this type of engine rises and 40 lowers twice during each revolution of the cranks, being highest when the two pairs of pistons and corresponding cranks are, respectively, at top and bottom dead centers and 45 lowest when the cranks are at 90° from this position. A mechanism suspended in such a way that it is free to move in all directions tends to maintain its total center of gravity 50 fixed in space. Therefore, if the center of gravity of a part of the mechanism moves in one direction the remainder of the mechanism tends to shift in the opposite direction. Accordingly, in the present instance, the engine 55 block tends to assume its highest position, in response to the inertia forces of the reciprocating parts, when the cranks are in a horizontal position and its lowest position when the cranks are at top and bottom dead centers, the intermediate positions following

substantially a sine curve. The amplitude of movement may also be derived from the computation of the disturbing force, by well-known text-book methods, and a comparison of respective masses of the reciprocating and non-reciprocating parts.

Various modifications in details and mechanical expedients may, of course, be employed in carrying out the invention without departing from the spirit and scope thereof and therefore we do not wish to be restricted to the specific features herein described except as required by the language of the appended claims in view of the prior art.

We claim:

1. A mounting for bodies subject to vibrations, comprising the combination of a base means for supporting the body from the base and means for moving said supporting means in synchronism with the said vibrations and in a direction and to such extent as to permit the body to vibrate without transmission of the energy of such vibrations through the supporting means to the base.

2. The combination with a body having moving parts causing vibration and a base by which the body is supported of connecting means between said body and base and means actuated independently of the vibrations to positively adjust the connecting means to compensate for the vibratory movement and permit the vibration without transmitting the energy thereof to the base.

3. The combination with an engine subject to vibration at the point of support, and a base therefor of supporting means between said engine and base and means actuated by a moving part of the engine to adjust said supporting means in synchronism with the said vibrations in such manner as to permit the engine to move in accordance with said vibrations without transmitting the energy thereof to the base.

4. Structure in accordance with claim 3 including a lever whereby the engine is supported and means for causing oscillations of said lever.

5. The combination of an engine subject to vibration, a frame, a lever pivotally connected to said frame and to said engine, said lever constituting a positioning element whereby the engine is positioned relatively to the frame, and means for causing oscillations of said lever in a direction and with an amplitude to permit said vibrations without transmitting the energy thereof to the frame.

6. Structure as set forth in claim 3, the last-mentioned means including a cam actuated by the engine.

7. The combination with mechanism having moving parts tending to cause vibration of said mechanism, of a base, means connecting said mechanism to said base including an oscillating part adapted to vary the distance between the mechanism and the base and

means for actuating said oscillating part in synchronism with said vibrations to permit the mechanism to vibrate without transmitting the energy of such vibrations to the base.

8. Structure as set forth in claim 7, said last mentioned means being actuated by a moving part of the said mechanism.

9. A mounting for bodies subject to vibrations comprising, in combination with the body, a base, means for positioning the body relatively to the base, and means for reducing the transmission of the energy of said vibrations to the base comprising mechanism for continuously moving said positioning means in synchronism with the said vibrations, and in direction and to extent to permit the body to vibrate without opposing substantial resistance to the vibrations.

10. A mounting for bodies subject to vibrations comprising, in combination with the body, a base, means for positioning the body relatively to the base, and means for continuously moving the positioning means to maintain the body in predetermined relation to the base, said relation being varied in synchronism with said vibrations and in direction and to extent to permit the movement of the body relatively to the base in accordance with the said vibrations.

11. A body including moving parts operative to set up vibrations of said body, a base therefor and means for preventing transmission of the energy of such vibrations to the base comprising connecting means having a non-resilient part between said base and said body and means for moving the said non-resilient part in synchronism with the said vibrations and in a direction to permit the body to vibrate relatively to the base.

12. In an engine mounting, the combination with an engine subject to vibrations of a supporting frame, means connecting the engine to said frame including a non-resilient part, and means acting upon said connecting means to move the said non-resilient part to permit the position of the engine to vary relatively to the frame in synchronism with vibrations in said engine.

13. The structure as set forth in claim 12, the means for moving the non-resilient part being actuated by a moving part of the engine.

14. The structure as set forth in claim 12, the means for moving the non-resilient part being actuated by the engine cam shaft.

15. The combination of a machine subject to vibrations of substantially fixed amplitude and direction, a support, means connecting the machine and the support, and means for positively moving said connecting means in synchronism with said vibrations so as to cause the point of support to follow the machine in its vibratory movement to prevent transmission of vibrations to the support.

16. A mounting for machines subject to vibrations due to inherent unbalance comprising the combination with such machine of a supporting base therefor and means for moving the machine relatively to the base at the points of support in the approximate direction and with approximately the same phase relation and amplitude with which the machine tends to move due to its inherent unbalance to reduce thereby the transmission of the energy of such vibrations to the base.

17. The combination with an engine and supporting chassis, such engine being subject to vibrations due to inherent unbalance of moving parts, of means for moving the engine relatively to the chassis at a point of connection of the engine to the chassis in the approximate direction and with approximately the same phase relation and amplitude with which the engine tends to move due to such inherent unbalance to reduce thereby the transmission of the energy of such vibrations to the chassis.

In testimony whereof we affix our signatures.
